CLAIM

The ornamental design for a vanity cabinet, as shown and described.

DESCRIPTION

FIG. 1 is a top perspective view of a vanity cabinet showing our new design;

FIG. 2 is a top plan view thereof;

FIG. 3 is a front elevation view thereof;

FIG. 4 is a side elevation view thereof; and,

FIG. 5 is a side elevation view thereof showing the side opposite from that shown in FIG. 4.

The bottom and rear views (not shown) form no part of the claimed design. The subject matter shown in broken lines is for illustrative purposes only and forms no part of the claimed design.
